CLAIM

The ornamental design for a children balance bike, as shown and described.

DESCRIPTION

FIG. 1 is a bottom, front and left side perspective view of the children balance bike showing my new design;

FIG. 2 is a top, rear and right side perspective view thereof;

FIG. 3 is a left side elevation view thereof;

FIG. 4 is a right side elevation view thereof;

FIG. 5 is a front elevation view thereof;

FIG. 6 is a rear elevation view thereof; and

FIG. 7 is a top plan view thereof;

FIG. 8 is a bottom plan view thereof; and,

FIG. 9 is a top, rear and left side perspective view of another state of the children balance bike thereof.

The broken lines in the drawing depict portions of the children balance bike that form no part of the claimed design.
